CLAIM

The ornamental design for a cooking pan-immobilizing stand for a stove top grate, as shown and described.

DESCRIPTION

FIG. 1 is a front perspective view of a cooking pan-immobilizing stand for a stove top grate showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is an elevational view of one side thereof; and,

FIG. 7 is an elevational view of the other side thereof.

The broken line showing of the stove top in FIG. 2 is for illustrative purposes only and forms no part of the claimed design.

FIG. 1.

FIG. 2.

FIG. 3.

FIG. 4.

FIG. 5.

FIG. 6.

FIG. 7.
